CYANINE DYES CONTAINING A 3,4-DIHYDROISOQUINOLINE NUCLEUS

Leslie G. S. Brooker and Robert H. Sprague,
Rochester, N. Y., assignors to Eastman Kodak
Company, Rochester, N. Y., a corporation of
New Jersey

No Drawing. Application March 20, 1948,
Serial No. 16,146

6 Claims. (Cl. 260—240.65)

1

This invention relates to cyanine dyes containing a 3,4-dihydroisoquinoline nucleus and to a process for preparing such dyes.

1-methyl-3,4-dihydroisoquinoline is a known base, having been described by Späth et al., Ber. 63, 134 (1930). We have prepared alkyl quaternary salts of this base by heating the base with alkyl salts. These quaternary salts, we have found, can be condensed with trialkyl orthoformates to give carbocyanine dyes, and with other substances to give still other cyanine and styryl dyes. This is surprising, since alkyl quaternary salts of 1-methylisoquinoline cannot be condensed with trialkyl orthoformates to give carbocyanine dyes. See the copending application of F. L. White and L. G. S. Brooker, Serial No. 672,340, filed May 25, 1946 (now United States Patent 2,466,523, dated April 5, 1949). Moreover, 1-methyl-3,4-dihydroisoquinoline quaternary salts do not condense with trialkyl orthoacetates or orthopropionates to give carbocyanine dyes.

It is, accordingly, an object of our invention to provide new cyanine and styryl dyes containing a 3,4-dihydroisoquinoline nucleus. It is a further object to provide a process for preparing such dyes. Still other objects will become apparent hereinafter.

In accordance with one embodiment of our invention, we condense a trialkyl orthoformate with a 1-methyl-3,4-dihydroisoquinoline alkyl quaternary salt selected from those represented by the following general formula:

I.

wherein R represents an alkyl group, i. e. an alcohol radical, e. g. methyl, ethyl, n-propyl, n-butyl, isobutyl, n-amyl, isoamyl, β -hydroxyethyl, γ -hydroxypropyl, β -methoxyethyl, β -ethoxyethyl, allyl, benzyl, phenylmethyl, β -phenylethyl, β -carboxyethyl, carboxymethyl, α -carboxyethyl, γ -carboxypropyl, β -acetoxymethyl, γ -acetoxymethyl, carbomethoxymethyl, carbethoxymethyl, β -carbomethoxyethyl, β -carbethoxyethyl, etc. and X represents an anion, e. g. benzene-sulfonate, p-toluenesulfonate, methylsulfate, ethylsulfate, chloride, bromide, iodide, perchlorate, thiocyanate, sulfamate, acetate, propionate, butyrate, etc.

As trialkyl orthoformates, the following are examples: trimethyl orthoformate, triethyl orthoformate, tri-n-propyl orthoformate, tri-n-butyl orthoformate, n-propylidethyl orthoformate, triisoamyl orthoformate, etc. The condensations are advantageously effected in pyridine.

The dyes obtained by these condensations can be represented by the following general formula:

II.

2

wherein R and X have the values given above. We have found that the 1-methyl-3,4-dihydroisoquinoline alkyl quaternary salts can be condensed with cyclammonium quaternary salts containing a thioether group in a reactive position (i. e. the alpha or gamma position), e. g. cyclammonium quaternary salts having the following general formula:

wherein X has the value given above, R1 represents an alkyl or aryl group, e. g. methyl, ethyl, n-propyl, n-butyl, benzyl, phenyl, p-chlorophenyl, β -naphthyl, etc., R2 represents an alkyl group, e. g. those given above under R, n represents a positive integer of from 1 to 2, and Q represents the non-metallic atoms necessary to complete a heterocyclic nucleus containing from 5 to 6 atoms in the heterocyclic ring. Typical of these thioether compounds represented by Formula III are: 2-methylmercapto-benzothiazole metho-p-toluenesulfonate, 2-phenylmercaptoquinoline ethiodide, 2-ethylmercapto-5,6-dimethoxybenzothiazole etho-p-toluenesulfonate, 2-methylmercaptobenzoxazole etho-p-toluenesulfonate, 2-methylmercapto-5,6-dimethylbenzoxazole etho-p-toluenesulfonate, 2-methylmercapto- β -naphthoxazole etho-p-toluenesulfonate, 2-methylmercapto-5-methylbenzoxazole etho-p-toluenesulfonate, 2-methylmercaptobenzothiazole ethiodide, 2-(p-chlorophenylmercapto)quinoline ethiodide, 2-(2-benzothiazolylmercapto)quinoline ethiodide, 2-(β -naphthylmercapto)pyridine ethiodide, 2-(p-tolylmercapto)quinoline ethiodide, 4-phenylmercapto-pyridine methiodide, etc.

45 The condensations are advantageously carried out in the presence of a basic condensing agent, e. g. tertiary amines, such as triethylamine, tri-n-propylamine, triisoamylamine, N-methylpiperidine, N-ethylpiperidine, triethanolamine, etc. Diluents may also be used, e. g. lower aliphatic alcohols, for instance, ethyl alcohol, isopropyl alcohol, n-propyl alcohol, n-butyl alcohol, etc.

The monomethine dyes obtained by these condensations can be represented by the following general formula:

IV.

wherein n , R , R_2 , Q and X have the values given above.

We have also found that the 1-methyl-3,4-dihydroisoquinoline alkyl quaternary salts can be condensed with p-dialkylaminobenzaldehydes, e. g. p-dimethylaminobenzaldehyde, p-diethylaminobenzaldehyde, etc. to give styryl dyes. The condensations are advantageously carried out in the presence of a secondary amine, e. g. piperidine, 2-methylpiperidine, 4-methylpiperidine, 6-methylpiperidine, etc. Diluents are advantageously employed, e. g. ethyl, isopropyl, n-propyl, or n-butyl alcohols.

The styryl dyes obtained by these condensations can be represented by the following general formula:

v.

wherein R and X have the values given above and R_3 and R_4 each represents an alkyl group.

We have also found that the 1-methyl-3,4-dihydroisoquinoline alkyl quaternary salts can be condensed with pyrrole carboxaldehydes selected from those represented by the following general formula:

vi.

wherein R_5 represents an alkyl group, e. g. methyl, ethyl, etc. and R_6 represents an alkyl group or an aryl group, e. g. methyl, ethyl, decyl, lauryl, cetyl, β -hydroxyethyl, phenyl, p-chlorophenyl, etc. The condensations are advantageously carried out in a solvent, e. g. methyl, ethyl, n-propyl, isopropyl, isobutyl, or n-butyl alcohol.

The pyrrolocyanine dyes obtained by this condensation can be represented by the following general formula:

vii.

wherein R , R_5 , R_6 and X have the values given above.

The following examples will serve to illustrate further the manner of obtaining our new dyes and the alkyl quaternary salts of 1-methyl-3,4-dihydroisoquinoline.

Example 1. — 2,2'-diethyl-3,4,3',4'-tetrahydro-1,1'-isoquinocarbocyanine perchlorate

1.45 g. (1 mol.) of 1-methyl-3,4-dihydroisoquinoline and 2.0 g. (1 mol.) of ethyl p-toluenesulfonate were heated together for one hour at 110° C. The viscous product was washed by de-

cantation with 25 cc. of ether. 1.5 g. (2 mols.) of ethylorthoformate and 20 cc. of pyridine were added and the mixture boiled under reflux for 30 minutes. The red solution was cooled, diluted with 200 cc. of ether and chilled to 0° C. The ether layer was decanted off and the sticky residue dissolved in 10 cc. of absolute ethyl alcohol. The dye was precipitated by addition of an aqueous solution of sodium perchlorate. The dye was collected on a filter, washed on the filter with water and dried. The yield of red crystals was 1.8 g., 79 per cent. After recrystallization from methyl alcohol (75 cc. per gram) the product was obtained as red needles with a bright reflex melting with decomposition at 215–216° C. Yield 1.5 g., 66 per cent.

Example 2.—1-methyl-3,4-dihydroisoquinoline metho-p-toluenesulfonate

20

25

3.8 g. (1 mol.) of 1-methyl-3,4-dihydroisoquinoline and 4.9 g. (1 mol.) of methyl p-toluenesulfonate were heated together at 110° C. for 30 minutes. The crystalline solid product was cooled, crushed under 25 cc. of acetone, chilled to 0° C. and collected on a filter. The product was washed with acetone on the filter and dried. The yield of white crystals was 8.3 g., 95 per cent.

Example 3.—1-methyl-3,4-dihydroisoquinoline etho-p-toluenesulfonate

45

29.0 g. (1 mol.) of 1-methyl-3,4-dihydroisoquinoline and 40.0 g. (1 mol.) of ethyl p-toluenesulfonate were heated together at 120–125° C. for 96 hours. The viscous brown product crystallized after standing at room temperature for four days. The crystals were stirred with 25 cc. of hot acetone, chilled to 0° C. and collected on a filter. The product was washed on the filter with acetone and dried. The yield of colorless crystals was 24.1 g., 35 per cent.

Example 4.—2,2'-dimethyl-3,4,3',4'-tetrahydro-1,1'-isoquinocarbocyanine iodide

65

1.65 g. (2 mols.) of 1-methyl-3,4-dihydroisoquinoline metho-p-toluenesulfonate, 0.75 g. (2 mols.) of ethylorthoformate and 20 cc. of pyridine were boiled together under reflux for 30 minutes. The red solution was cooled, diluted with 150 cc. of ether and chilled to 0° C. The ether was decanted off and the sticky residue dissolved in 10 cc. of hot methyl alcohol. The dye was precipitated from this solution by the addition of excess sodium iodide dissolved in methyl alcohol and dilution of the mixture to 150 cc. with water. The

red crystals of dye were collected on a filter, washed on the filter with water and acetone and dried. The yield of red needles of dye was 0.7 g., 61 per cent. After recrystallization from methyl alcohol (20 cc. per gram of dye) the product was obtained as bright red needles melting with decomposition at 263-264° C. Yield 0.45 g., 40 per cent.

Example 5.—1-p-dimethylaminostyryl-3,4-dihydroisoquinoline methoperchlorate

1.65 g. (1 mol.) of 1-methyl-3,4-dihydroisoquinoline etho-p-toluenesulfonate, 0.75 g. (1 mol.) of p-dimethylaminobenzaldehyde, 2 drops of piperidine and 15 cc. of absolute ethyl alcohol were boiled together under reflux for one hour. The red solution was cooled, diluted with 150 cc. of ether and chilled to 0° C. The ether solution was decanted from the sticky precipitate of dye and the dye dissolved in 10 cc. of hot methyl alcohol. The dye was precipitated as the perchlorate by addition of excess aqueous sodium perchlorate solution. The alcohol solution was decanted off and the dye stirred with 25 cc. of hot absolute ethyl alcohol until crystalline. The dye was collected on a filter, washed on the filter with alcohol and dried. The yield of red crystals was 0.4 g., 20 per cent. After recrystallization from absolute ethyl alcohol (100 cc. per gram) the dye was obtained as red crystals melting with decomposition at 154-156° C. Yield 0.3 g., 15 per cent.

Example 6.—1-p-dimethylaminostyryl-3,4-dihydroisoquinoline methoperchlorate

3.45 g. (1 mol.) of 1-methyl-3,4-dihydroisoquinoline etho-p-toluenesulfonate, 1.5 g. (1 mol.) of p-dimethylaminobenzaldehyde, 2 drops of piperidine and 15 cc. of absolute ethyl alcohol were boiled together under reflux for 45 minutes. A solution of 2.25 g. (1 mol. + 50 per cent excess) of sodium iodide in 5 cc. of methyl alcohol was added and the mixture was chilled to 0° C. The dye was collected on a filter, washed on the filter with acetone and water and dried. The yield of red crystals was 1.8 g., 42 per cent. After recrystallization from methyl alcohol (58 cc. per gram) the dye was obtained as red needles with a green reflex melting with decomposition at 240-242° C. Yield, 1.3 g., 30 per cent.

Example 7.—1-Ethyl-2',5'-dimethyl-1'-phenyl-3,4-dihydro-1-isoquino-3'-pyrrolocyanine iodide

3.45 g. (1 mol.) of 1-methyl-3,4-dihydroisoquinoline etho-p-toluenesulfonate, 1.75 g. (1 mol.) of 2,5-dimethyl-1-phenyl-3-pyrrolecarboxaldehyde, 2 drops of piperidine and 15 cc. of absolute ethyl alcohol were boiled together under reflux for 45 minutes. The solution was cooled, diluted with 150 cc. of ether and chilled to 0° C. The ether solution was decanted from the sticky precipitate of dye and the dye dissolved in 15 cc. of hot methyl alcohol. A solution of 2.5 g. (1 mol. + 100 per cent excess) of sodium perchlorate in 10 cc. of hot methyl alcohol was added and the mixture chilled to 0° C. The dye was collected on a filter, washed on the filter with water and dried. The yield of yellow crystals was 1.3 g., 29 per cent. After recrystallization from absolute ethyl alcohol (20 cc. per gram) the dye was obtained as heavy yellow crystals melting with decomposition at 193-195° C. Yield 1.0 g., 22 per cent.

Example 8.—1',2-diethyl-3,4-dihydro-1-isoquino-2'-cyanine iodide

3.45 g. (1 mol.) of 1-methyl-3,4-dihydroisoquinoline etho-p-toluenesulfonate, 4.4 g. (1 mol.) of 2-phenyl-mercaptoisoquinoline etho-p-toluenesulfonate, 1.0 g. (1 mol.) of triethylamine and 25 cc. of absolute ethyl alcohol were boiled together under reflux for 15 minutes. The dye was precipitated from the red solution by addition of 3.0 g. (1 mol. + 100 per cent excess) of sodium iodide dissolved in 15 cc. of hot methyl alcohol. The dye was collected on a filter, washed on the filter with water and acetone and dried. The yield of red crystals was 2.5 g., 55 per cent. After recrystallization from methyl alcohol (75 cc. per gram) the dye was obtained as red crystals with a green reflex which had a melting point of 270-272° C. Yield 2.0 g., 44 per cent.

In a manner similar to that shown in the foregoing examples other dyes of our invention can be prepared.

The pyrrole carboxaldehydes employed herein can be prepared by condensing formamide with a pyrrole base selected from those represented by the following general formula:

VIII.

wherein R5 and R6 have the values given above, in the presence of phosphorus oxychloride, according to the method of Nenitzescu and Isacescu, Bull. Soc. Chim. Roumania 11, 135 (1929). Details of this preparation are also given by Brooker and Sprague, Jour. Am. Chem. Soc. 67, 1869 (1945), and by Brooker and Sprague in United States Patent 2,409,612, dated October 22, 1946. The pyrrole bases of Formula VIII can be prepared according to the process of Lions et al., Proc. Royal Soc., New South Wales 71, 92 (1937).

The dyes disclosed herein sensitize photographic silver halide emulsions. Some, e. g. the dyes of Examples 5, 6 and 7 are bleached by the ordinary alkaline photographic developers and hence are useful in preparing bleachable filter layers for photographic elements.

What we claim as our invention and desire to be secured by Letters Patent of the United States is:

1. The dyes containing a 3,4-dihydroisoquinoline nucleus which are represented by the following general formula:

wherein R represents a primary alkyl group of the formula C_mH_{2m+1} wherein m represents a positive integer of from 1 to 4 and X represents an anion.

2. The dye which is represented by the following formula:

3. The dye which is represented by the following formula:

4. A process for preparing a carbocyanine dye comprising condensing a 1-methyl-3,4-dihydroisoquinoline alkyl quaternary salt selected from

5

those represented by the following general formula:

10 wherein R represents a primary alkyl group of the formula C_mH_{2m+1} wherein m represents a positive integer of from 1 to 4 and X represents an anion, with a trialkyl orthoformate.

15 5. A process for preparing 2,2'-diethyl-3,4,3',4'-tetrahydro-1,1'-isoquinocarbocyanine perchlorate comprising condensing 1-methyl-3,4-dihydroisoquinoline etho-p-toluene sulfonate with ethylorthoformate.

20 6. A process for preparing 2,2'-dimethyl-3,4,3',4'-tetrahydro-1,1'-isoquinocarbocyanine iodide comprising condensing 1-methyl-3,4-dihydroisoquinoline metho-p-toluenesulfonate with ethylorthoformate.
